Primary Examiner — Ian Simmons*Assistant Examiner* — Richelle Shelton(74) *Attorney, Agent, or Firm* — Eric D. Levinson(57) **CLAIM**

The ornamental design for a respirator belt, as shown and described.

DESCRIPTION

FIG. 1 is a front perspective view showing the new design for a respirator belt;

FIG. 2 is a front view thereof;

FIG. 3 is a back view thereof;

FIG. 4 is a top view thereof;

FIG. 5 is a bottom view thereof;

FIG. 6 is a left view thereof; and,

FIG. 7 is a right view thereof.

The broken line showing of portions of the article is included for the purpose of illustrating environmental structure and forms no part of the claimed design.

The shading is provided to illustrate contour only and is not an indication of surface texture.
